FRIEND A. RUSS, OF GREENWICH, CONNECTICUT, ASSIGNOR TO ROBERT N. BASSETT COMPANY, OF SHELTON, CONNECTICUT, A CORPORATION OF CONNECTICUT.

BUCKLE.

1,184,214.

Specification of Letters Patent. Patented May 23, 1916.

Application filed July 24, 1915. Serial No. 41,641.

To all whom it may concern:

Be it known that I, FRIEND A. Russ, a citizen of the United States, residing at Greenwich, in the county of Fairfield and State of Connecticut, have invented a certain new and useful Improvement in Buckles, of which the following is a specification.

My invention relates to buckles of the lever type, and more particularly to that 10 class of the same which are used on running webbing.

One of the objects of my invention is to provide a device of this character which is 15 capable of being strung in such a manner that the web is interposed between the buckle and garments to prevent any dampness or moisture in the latter from coming into contact with the buckle, thereby producing what is known in the trade as the 20 rustless effect.

Another object of my invention is to produce a buckle which can be made out of a small amount of metal and in which a minimum 25 length of webbing may be utilized to effect a maximum adjustment.

I attain these objects of my invention in the preferred embodiment thereof set forth in the following description and accompanying 30 drawings in which like reference characters refer to corresponding parts.

In the drawings: Figure 1 is a front view of my buckle strung with webbing a portion of which latter is broken away; Fig. 2, a 35 vertical section of the buckle shown in Fig. 1; Fig. 3 is a top view of the lever; Fig. 4, a vertical section of the back before the webbing is attached; Fig. 5, a front view of a modification and portion of the webbing 40 being broken away; Fig. 6, a vertical section of the buckle shown in Fig. 5, and Fig. 7, a detail view of a further modification.

My buckle generally comprises the frame or back A and the lever B. The back A is 45 suitably blanked and struck up out of sheet metal to form the back plate 2 having the forwardly turned side ears 3, 3 which latter are provided with perforations one of which is shown at 4. Immediately below the top 50 edge 5 of the back plate 2 the metal is depressed to form a channel 6 the purpose of which will hereinafter appear. The bottom of the back 2 is provided with a transversely disposed web-holding lip 7. This 55 lip 7 is of such a length that when the same is

folded up toward the front face of the back plate its edge 8 will lie substantially in front of the channel or depression 6. The lever B is also made out of a sheet metal blank the top portion of which is cut away and bent 60 at an angle, as shown in Figs. 1 and 3, to form the web-engaging member 9 and the side covers or shelves 10, 10 which latter carry laterally projecting trunnions 11, 11. The web-engaging member 9 is provided 65 with web-holding teeth 12. The trunnions are journaled in the perforations in the side ears 3, 3 thereby enabling the lever to be manipulated by the front portion 13 when the buckle is being opened and closed. The 70 webbing C is fastened to the frame A by passing the extremity k over the front face of the back plate 2 until it strikes the forwardly projecting lip 7 which latter is then pressed toward the front face of the back 75 plate and suitably swaged to permanently secure the extremity k between the lip 7 and the back plate 2. The extremity k being thus secured the free or moving portion of the webbing is passed rearwardly over 80 the top edge 5 of the back plate then downwardly below the back and then upwardly between the lever and the back plate into the upper reach. When the lever B is shut down it locks the webbing against the back 85 plate 2 in a manner which will hereinafter be fully described. The buckle thus strung forms an adjustable loop in the webbing which carries the cast-off member D or any other member. The lip 7 not only performs 90 the function of holding the extremity k of the webbing and presenting a snap over edge to the lever, but also forms a backing for the moving portion of the webbing, thereby preventing the latter from coming into contact 95 and drawing on the fixed extremity during the time that the lever edge is approaching the top of the lip. This arrangement prevents the fixed extremity from being pulled out from behind the lip. While the lever 100 constructed as shown possesses inherent advantages when adapted to my buckle, yet I may use any suitable lever wherein the snap over and deflecting action of the lever edge is still maintained, and should the webbing 105 holding the lip be eliminated the extremity of the webbing may be secured to the back in any other suitable manner.

Referring to the modification shown in Figs. 5 and 6, the back plate is slotted trans-

versely to form top and bottom bars 14 and 15. The metal of the top bar is depressed forwardly immediately adjacent to its top edge 16 to form a ridge or shoulder 17 and a 5 channel or counter depression 18 above the ridge. The lever B' comprises a front member 19 and a web-engaging member 20 which latter is provided with laterally projecting trunnions journaled in the perforated side 10 ears 21, 21. The webbing is folded rearwardly around the bar 14 and is stitched upon itself at s forming a terminal attaching loop. Having been thus secured to the back of the buckle the webbing is passed 15 downwardly below the back and then upwardly between the lever and back into an upper reach, thereby forming an adjustable loop carrying the cast-off member D. In closing the lever on the webbing the edge of 20 the web-engaging member 20 snaps over the ridge or shoulder 17 and deflects the webbing into the channel 18. This snap over and deflecting action of the lever edge securely locks the moving portion of the webbing and holds the lever closed.

In the above disclosed forms of my invention the buckle is shown strung rustless so that there are two layers of webbing between the edge of the lever and the back. 30 The buckle, however, is adapted to be strung in various other ways, a particular instance being shown in Fig. 7 in which only a single layer of webbing is interposed between the edge of the lever and the back. In this 35 modification the back plate 22 is suitably depressed adjacent to its top edge to form a shoulder 23 and a channel 24. The lever 25 is journaled in the perforated side ears, one of which is shown at 26, so that its edge 40 snaps by the shoulder into the channel and grips the webbing in the same manner as in the preceding figures. The extremity k of the webbing is passed through the slot 27 in the back plate 22 and is then folded downwardly and stitched on itself at s, forming a terminal attaching loop. The moving portion of the webbing is passed between the lever and the back.

Although the device above described embodies the preferred forms of my invention yet the same is susceptible to such further modification as may fairly come within the scope of the appended claims.

This application is a continuation of my 55 prior application filed March 8, 1912, Serial No. 682,361, for buckles, insomuch as this application refers to Figs. 1, 2, 3, 4 and 7.

Having now described my invention what I claim and desire to protect by Letters 60 Patent is:

1. A buckle comprising a pivoted lever and a sheet metal back plate having forwardly turned side ears, the said back plate

being provided with a transversely disposed channel adjacent to its top edge and having 65 its lower portion bent forwardly to form a transversely disposed web-gripping lip folded toward the front face of said plate so that its free edge will lie in front of said channel, combined with a running webbing 70 having its extremity gripped between said lip and back plate and its free portion passed rearwardly over the top edge of the back plate and then looped downwardly below the back and passed upwardly between 75 the lever and back, and the said lever having its web holding edge arranged to snap over the edge of said lip and to press the webbing into said channel to hold the buckle closed. 80

2. A buckle for webbing comprising a sheet metal back plate having forwardly turned side ears, the said back plate being channeled transversely adjacent to its top edge and having its lower portion bent forwardly to form a transversely disposed web gripping lip adapted to be folded toward 85 the front face of said plate so that its extremity will lie substantially even with the lower side of said channel, and a lever pivotally mounted between said ears and arranged to coat with the top side of said lip and to swing into said channel to hold the buckle closed when strung with webbing. 90

3. A buckle for webbing having a sheet 95 metal back plate, the said back plate being provided with a transversely disposed channel adjacent to its top edge, and a lever pivotally mounted in front of said plate, the said lever having its web-holding edge arranged to snap into said channel to hold the 100 buckle closed.

4. In a buckle for webbing a sheet metal back plate having its top edge depressed rearwardly to form a transversely disposed 105 channel and having that portion below the channel provided with means for holding the end of a webbing fast to the back plate, and a lever pivotally mounted in front of the plate, the said lever having its web-holding edge arranged to snap into the channel 110 to hold the buckle closed.

5. A buckle for webbing comprising a back bent up out of sheet metal to form a pair of transversely disposed lips which are 115 adapted to be permanently swaged on to the end of a webbing, and a lever hinged to said back, the said lever having its web-locking edge arranged to snap by the top edge of the front lip and to coöperate with 120 the rear lip to pinch the moving portion of the webbing when the buckle is closed.

In testimony whereof I have hereunto set my hand this 22 day of June, 1915.

FRIEND A. RUSS.
